(57) **CLAIM**

The ornamental design for an adhesive attachment for magnetic mounting bracket, as shown and described.

DESCRIPTION

FIG. 1 is a front perspective view showing a first embodiment of the adhesive attachment for magnetic mounting bracket of the present invention with those features shown in phantom presented for exemplary purposes only

FIG. 2 is a back perspective view thereof;

FIG. 3 is a top plan view thereof;

FIG. 4 is a front view thereof;

FIG. 5 is a left side thereof;

FIG. 6 is right side view thereof;

FIG. 7 is a rear view thereof; and,

FIG. 8 is a bottom view thereof.

1 Claim, 3 Drawing Sheets
